UNITED STATES PATENT OFFICE.

FRANCIS H. JOYNER, OF RICHMOND, VERMONT.

RAILROAD-SWITCH.

Specification of Letters Patent No. 26,270, dated November 29, 1859.

To all whom it may concern:

Be it known that I, FRANCIS H. JOYNER, of Richmond, in the county of Chittenden and State of Vermont, have invented a new and Improved Railroad-Switch; and I do hereby declare that the following is a full, clear, and exact description of the construction and operation of the same, reference being had to the annexed drawing, making a part of this specification, (which drawing is a perspective view of said railroad-tracks and switch,) and to the letters of reference marked thereon.

(a) and (b) represent two continuous rails, constituting at the end near the observer a single track, and, at the other, the outside rails of two tracks. (c) and (d) are the inside rails of those tracks, (d) forming with (a) the left, and (c) with (b) the right track. They are continued toward the observer until they come so near the outside rails, (a) and (b), as barely to permit the flange of the car wheel to pass freely between them. They are then tapered to a point still preserving the same distance from the outside rails, and are plated with steel. Where they terminate the rails (a) and (b) are so near, that, while one car-wheel is running on the rail (a) approaching the be-holder, the tread of the other, which has been running on (d), will lap over and be sustained on the rail (b).

(E) and (e) are switch rails with the nearer ends slightly curved inward, and resting on chairs, in which they have some slight play as on pivots. The other ends curve inward still more, and slide on suitable chairs, and are moved by a switch rod in any usual manner. The curve is such that, when thrown to the left, the left rail presses against the left wheel of a car going out and forces it into the left track; and the reverse when thrown to the right.

When the switch is adjusted for the left track, it is obvious that a locomotive coming over that track will be safely conducted upon the single track. And, if it comes in that case on the right track, the same result will follow, since the rails (a) and (b) are so near together as to sustain both wheels, where it leaves the rail (c). But, in order to secure this more effectually, such a curve must be given to the switch rails that, while a car-wheel can pass between the rail (c) and the switch rail on that side, when thrown to the left, yet, before the wheel drops off the rail (c), it will strike the switch rail, and be forced upon the rail (a).

The advantages of this arrangement are, that the bearing rails are all stationary and firm; that the switch rail may be made light and less expensive; and especially that, while the trains may be directed with sufficient certainty upon either branch, as desired, it is practically impossible for them to run off the track, whichever way they are moving, and however the switch may be adjusted.

Switches have heretofore been constructed with stationary rails, the inner approaching the outer ones, and made tapering and the whole arranged like the stationary rails above described. But no adequate provision was made in them for the safety of trains coming on one side track, when the switch was adjusted for the other.

Therefore, what I claim as my invention, and desire to secure by Letters Patent, is—

A pair of switch rails, in connection with stationary bearing rails, the whole constructed and arranged as is described above.

F. H. JOYNER.
